US0D1035908S

(12) **United States Design Patent** (10) Patent No.: **US D1,035,908 S**
(45) Date of Patent: ** Jul. 16, 2024

(54) **INSTRUMENT FOR MEDICAL OR
LABORATORY DIAGNOSIS**

(71) Applicant: **LVL technologies GmbH & Co. KG,**
Crailsheim (DE)

(72) Inventor: **Waldemar Janzen**, Ellwangen (DE)

(**) Term: **15 Years**

(21) Appl. No.: **35/514,735**

(22) Filed: **May 31, 2022**

(80) **Hague Agreement Data**

Int. Filing Date: **May 31, 2022**

Int. Reg. No.: **DM/222096**

Int. Reg. Date: **May 31, 2022**

Int. Reg. Pub. Date: **Jul. 22, 2022**

Primary Examiner — Omeed Agilee

(57) **CLAIM**

The ornamental design for an instrument for medical or
laboratory diagnosis, as shown and described.

DESCRIPTION

FIG. 1.1 is a perspective view from above of the invention;
FIG. 1.2 is a top view;

FIG. 1.3 is a bottom view in which the dashed lines depict
portions of the invention that form no part of the claimed
design;

FIG. 1.4 is a rear view;

FIG. 1.5 is a front view;

FIG. 1.6 is a side view from the left; and

FIG. 1.7 is a side view from the right.

1 Claim, 7 Drawing Sheets
